FIG. 4.

Attorney

UNITED STATES PATENT OFFICE.

CHARLES O. McCASLAND, OF ST. LOUIS, MISSOURI.

LIQUID-DISPENSING MACHINE.

1,420,327.

Specification of Letters Patent. Patented June 20, 1922.

Application filed August 5, 1920. Serial No. 401,466.

To all whom it may concern:

Be it known that I, CHARLES O. McCASLAND, a citizen of the United States, residing at St. Louis, in the county of St. Louis 5 and State of Missouri, have invented certain new and useful Improvements in Liquid-Dispensing Machines, of which the following is a specification.

The object of my invention is to provide a 10 liquid dispensing device, such for instance as a gasoline selling station, which may be located at predetermined points along a highway and which may be operated by the purchaser of the gasoline whereby a motorist 15 may obtain gasoline at any hour of the day or night.

A further object of my invention is to provide means whereby the purchaser may operate the dispensing device only after he 20 has inserted therein a prescribed coin or token.

A further object of my invention is to provide means whereby the machine may be set to deliver a predetermined amount of gasoline 25 for each coin or token introduced into the machine so that the fluctuation in price will not work against the owner of the machine; and with these and other objects in view my invention consists of the parts and 30 combination of parts as will be hereinafter set forth.

In the drawing:

Figure 1 is a vertical central section of a 35 gasoline dispensing machine embodying my invention, portions being in section and other portions broken away.

Figures 2 and 3 are enlarged detail views.

Figure 4 is an enlarged detail view of a slight modification.

Figure 5 is a vertical sectional view of a dispensing machine illustrating another embodiment of my invention.

The construction shown in this case is primarily designed to be connected with a supply 45 of gasoline in an elevated tank or an underground tank in which the gasoline is under pressure, but it may, as will be shown, be used with equal effectiveness in connection with the standard pump.

The reference numeral 1 designates a supply 50 pipe which may be connected with an elevated tank or a tank in which the gasoline is under pressure. This supply pipe 1 is coupled to the discharge pipe 2 and is 55 coupled to the measuring tank 3 by means of a short pipe 4. The supply pipe 1 is

provided with the shut off cock 5 between the supply tank and the short pipe 4 whereby the measuring tank 3 may discharge into the discharge pipe 2 when the supply pipe is 60 cut off. The discharge pipe 2 is provided with a shut off cock 8 which is provided with an arm 9. The cock 5 is provided with arms 6 and 7.

The tank 3 may be of any desired size and 65 is provided with a float 10 having a piston-like fit in the tank so that the pressure as well as the weight of the gasoline will move it so that when gasoline is admitted through the port 11 at the bottom of the tank the 70 float 10 will be forced upward and carry with it a rack bar 12 which meshes with a gear wheel 13 of a suitable meter, said gear wheel having mounted on its shaft an indicator which is visible to the purchaser, so that he 75 may see that he is getting the amount of gasoline he pays for.

A stopper 15 suspended on a rod 16 is adapted to close the port 11 when the float 10 has reached its uppermost limit and said 80 rod 16 is connected adjustably to the float by means of a nut 17 screw threaded on the rod whereby the length of the rod below the float may be regulated by threading through the nut 17 so that the length of movement of the 85 stopper 15 in closing the inlet port 11 may be adjusted according to the fluctuations of gasoline prices. For instance when the rod 16 is screwed downward in the nut 17 as far as it will go the full capacity of the tank 3 90 will be delivered. The meter to which the gear wheel 13 is connected shows the total amount of gasoline sold.

In order to lock the machine against unauthorized operation I provide a coin lock 18 95 of any suitable construction and provided with a coin chute 19 which chute extends through the casing.

A push bar 20, provided with a suitable handle 21 is slidable through a slot in the 100 wall of the casing 22, the handle 21 and adjacent portion of the bar being outside of the casing, and is locked against movement by means of the lock 18 and can only be moved after a prescribed coin or token has 105 been introduced into the lock. The inner end of the bar 20 is pivotally connected to one end of a link 22^a, the other end of the link being pivotally connected to the arm 9 of the cock 8 in the delivery pipe whereby 110 the cock may be operated.

A lever 23 is suitably pivoted in the casing

22 one end projecting outside of the casing through a suitable slot in the casing. One end of a link 24 is pivotally connected to the inner end of the lever 23 while its other end is suitably pivoted to the arm 6 of the cock 5 in the supply pipe 1. A bar 25 is pivotally suspended from the lever 23 and normally rests upon the sliding push bar 20 thereby preventing a movement of the lever 23 to 10 operate the device, but the bar 20 is provided with an interruption which, may be the shoulder 26 or the slot 27, which, when the bar 20 has been moved inwardly to the limit of its movement, permits the bar 25 to de- 15 scend as shown in Figure 3.

Upon the insertion of a coin or token in the lock 18 the bar 20 is free to be moved, whereupon it is pushed inward to the limit of its stroke, which movement operates the link 20 22^a and arm 9 whereby the cock in the discharge pipe 2 is closed. The lever 23 is now free to be moved upward thereby pushing the bar 25 downward back of the shoulder 26 or through the slot 27 thereby locking the 25 bar 20 against outward movement. As the lever 23 is moved upward at its outer end it pulls the link 24 downward thereby pulling the arm 6 and opening the cock 5 in the supply tank, whereupon the gasoline is free to 30 flow through the supply pipe into the measuring tank 3 forcing the float 10 upward until the stopper 15 closes the inlet 11 thereby shutting off the supply of gasoline to the measuring tank 3. When the purchaser sees 35 that the amount of gasoline purchased is in the measuring tank he then pushes the lever 23 downwardly thereby through the link 24 and arm 6 completely closing the cock 5 in the supply tank. The bar 20 is now re- 40 leased and may be pulled outwardly, which movement, through the link 22^a and arm 9 opens the valve 8 in the discharge pipe, whereupon the gasoline in the measuring tank 3 is free to flow therefrom into the tank 45 on an automobile or in any other receptacle, but the bar 20, after it has been moved sufficiently to open the valve 8 is immediately locked against inward movement until another coin has been inserted and the lever 50 23 is also locked against movement by reason of the bar 25 again resting upon the upper face of the bar 20.

In Figure 5 I have shown the above described mechanism adapted to a pump dispensing machine and as it is unnecessary to again minutely describe these parts I have used the same reference numerals in this figure as are used to designate like parts in the other figures.

60 In Figure 5 the gasoline supply pipe 1 leads into the measuring tank 3. The rack bar 27' is connected to a suitable pump adapted to be engaged by a pawl 28 said pawl being held normally in engagement 65 with the rack bar 27' by means of a coiled

spring 29, said pawl being connected by means of a rod, wire, or the like 30 to the arm 7 of the valve 5 in the supply pipe whereby the pump is locked by said pawl against unauthorized manipulation.

70 A second dog 31 is suitably pivoted in the casing 22, and is normally out of engagement with the rack bar 27'. This pawl 31 is connected by means of a rod, wire, or the like 32 to a counterbalanced rocking beam 75 33, also within the casing 22, said beam having depending lug or knob 34 at its free end. A rod 35 is mounted in a screw threaded nut 36 on the rack bar 12 of the float, and has its upper end projecting above the end 80 of the float rack bar for engagement with the knob 34 of the rocking beam 33, said rod 35 being adjustable to determine the amount of gasoline to be delivered for a 85 prescribed coin.

85 Referring to Figure 5, after the bar 20 cock 8, lever 23 and valve 5 have been given their initial movements, opening of the valve 5 through the arm 7 pulls on the rod 30 whereby the pawl 28 is disengaged from the pump rack bar 27 whereupon the pump is now free to be operated. When the prescribed quantity of gasoline has been delivered to the measuring tank the float has reached its uppermost portion and projected 90 its rack bar 12 and rod 10 upward and the rod 10 coming into engagement with the beam 33 rocks the beam on its pivot thereby lowering the rod 32 and permitting the pawl 31 to move into engagement with the pump rack 27' thereby locking the pump against further action. The push bar 20 and lever 23 are again operated as above described to open the discharge valve 8 and close the supply valve 5 whereby the pawl 95 28 is again permitted to move into engagement with the pump rack and the gasoline discharged, the downward movement of the float as the liquid is discharged permitting the pawl 31 to disengage from the pump 100 rack. The stopper 15 and the rod 16 would, of course, be detached when a pump was 105 used.

110 What I claim is:

1. The combination with a commercial 115 gasoline dispensing pump having the usual rack bar, a preliminary lock adapted to engage and lock the said bar against movement, means to release said lock, a measuring tank, means operated by a predetermined quantity of liquid in said tank to lock said bar against movement, a supply pipe and a discharge pipe for said tank, and a valved control for said pipes.

2. In a gasoline dispensing machine, the 120 combination with a measuring tank, and a valved supply and a valved discharge pipe, a lock controlled bar for the valve in the discharge pipe, means for operating the valve 125 in the supply pipe and detachably engag- 130

ing the said bar and inoperative while in engagement with said bar.

3. In a gasoline dispensing machine, the combination with a measuring tank, and a 5 valved supply and a valved discharge pipe therefor, a lock controlled bar for operating the valve in the discharge pipe, a lever for operating the valve in the supply pipe, and means interposed between said lever and 10 bar to hold the lever against operation until the said bar has been moved to close the discharge valve.

4. In a gasoline dispensing machine, the combination with a measuring tank, and a 15 valved supply and a valved discharge pipe therefor, of a lock controlled bar for operating the valve in the discharge pipe, a lever for operating the valve of the supply pipe, means carried by said lever and supported by said bar against downward movement until the bar has been moved to close the discharge valve, whereby the supply 20 valve cannot be opened until the discharge valve has been closed.

25 5. In a gasoline dispensing machine, the combination with a measuring tank, and a

valved discharge pipe and a valved supply pipe therefor, of a lock controlled bar for operating the discharge valve, a lever for operating the supply valve, a link depending 30 from said lever and supported on said bar when the discharge valve is open and the supply valve is closed, means on said bar to permit the link to descend when the bar has been moved to close the discharge valve 35 whereupon the lever may be operated to open the supply valve.

6. In a liquid vending machine, the combination of a measuring tank, a supply valve to and a discharge valve from said tank, 40 a lock-controlled means for operating said discharge valve, a means by which the operator may open or close said supply valve, a float, means operated by said float to prevent more than a predetermined quantity 45 of liquid entering the measuring tank while the supply valve is open, means to prevent the supply valve being opened while the discharge valve is open.

In testimony whereof I affix my signature. 50

CHARLES O. McCASLAND.
